US0D1091127S

(12) **United States Design Patent** (10) **Patent No.:** **US D1,091,127 S**
(45) **Date of Patent:** **** Sep. 2, 2025**

(54) **LUGGAGE**

(71) Applicant: **TUMI, INC.**, Edison, NJ (US)

(72) Inventor: **Victor G. Sanz**, Whitehouse Station, NJ (US)

(73) Assignee: **TUMI, INC.**, Edison, NJ (US)

(**) Term: **15 Years**

(21) Appl. No.: **29/899,525**

(22) Filed: **Aug. 9, 2023**

(51) LOC (15) Cl. **03-01**

(52) U.S. Cl. .... **USPC .....** **D3/279**

(58) **Field of Classification Search**

(57) **CLAIM**

The ornamental design for a luggage, as shown and described.

DESCRIPTION

FIG. 1 is a front perspective view of a luggage; FIG. 2 is a front view of the luggage of FIG. 1; FIG. 3 is a rear view of the luggage of FIG. 1; FIG. 4 is a top view of the luggage of FIG. 1; FIG. 5 is a bottom view of the luggage of FIG. 1; FIG. 6 is a right side view of the luggage of FIG. 1; and, FIG. 7 is a left side view of the luggage of FIG. 1. The broken lines shown in the figures illustrate structure or features that form no part of the claimed design. The drawings include surface shading that represents contour and not surface ornamentation or color.

1 Claim, 7 Drawing Sheets
